FOOD HANDLING APPARATUS

George R. Wood, Montreal, Quebec, Canada, assignor to Toledo Scale Company, Toledo, Ohio, a corporation of New Jersey

Application April 12, 1943, Serial No. 482,764

5 Claims. (Cl. 146—102)

This invention relates to food handling apparatus of the type in which a commodity to be sliced is reciprocated past an exposed edge of a rotary circular knife, a slice of commodity being severed during each forward stroke, and more particularly to means for determining the thickness of slices so severed.

A slicing machine is usually equipped with a gauge plate, which is erected on the machine with its face in a plane substantially parallel to the plane of the cutting edge of the knife and closely adjacent to the edge of the knife, and is movable in a direction substantially transverse to the plane of its face to vary the thickness of slices of commodity severed by the knife.

It is an object of this invention to provide a gauge plate for a slicing machine which is mounted for easy adjustment with respect to the knife to determine the thickness of slices to be severed.

It is another object of this invention to provide a gauge plate that is easily removable so that greases and fats which accumulate on its commodity engaging face readily can be cleaned therefrom.

It is a further object of this invention to provide a gauge plate for a slicing machine which is mounted in a manner tending to prevent particles of commodity which may crumble or be rubbed off the face of the commodity as it is slid across the face of the gauge plate from falling into the interior of the machine.

A still further object of this invention is to provide a gauge plate mounting comprising very simple parts which can be so assembled as to afford very few externally protruding dirt and grease catching portions.

More specific objects and advantages are apparent from the description, in which reference is had to the accompanying drawings illustrating a preferred form of slicing machine embodying the invention.

In the drawings:

Fig. I is a fragmentary view, partly in elevation and partly in section, of a slicing machine incorporating a gauge plate embodying the invention.

Fig. II is a fragmentary vertical sectional view of the mechanism shown in Fig. I, taken substantially from the position indicated by the line II—II in Fig. I.

Fig. III is a fragmentary view, in elevation, taken from the rear of Fig. I and shown on a slightly smaller scale.

Fig. IV is a fragmentary plan view of slice-receiving and gauge plate mounting means.

These specific drawings and the specific description that follows merely disclose and illustrate the invention and are not intended to impose limitations upon the claims.

5 A slicing machine embodying the invention comprises a circular rotary knife 10 which is drivingly connected to an electric motor 11 mounted on a main base 12. A commodity to be sliced by the knife 10 is carried in a reciprocable commodity supporter 13 and is slid along a forward face 14 of a gauge plate 15 until it passes the edge of the knife 10 and a slice of commodity is severed therefrom. A slice of commodity so severed is deflected by a deflector plate 16 onto the upper surface of a slice-receiving platter 17 which is mounted on the base 12 behind the gauge plate 15.

10 The gauge plate 15 is adjustably attached to a gauge plate mounting frame 18 by means of four screws 19 which pass through elongated holes 20 in the gauge plate mounting frame 18, and are threaded into tapped collars 21 welded on the back face of the gauge plate 15 and located in the interior of the gauge plate mounting frame 18 when assembled. The holes 20 are elongated in order that the relative position of the gauge plate and mounting frame 18 may be horizontally varied to move an edge 22 of the gauge plate which is adjacent the edge of the knife 10, radially of the knife to compensate for decreases in its diameter resulting from sharpening.

15 The gauge plate mounting frame 18 has a hollow interior through which there extends a web 23 in which is located a vertical bore 24 and two vertically-bored bosses 25. The center lines of the bore 24 and bosses 25 are parallel so that the gauge plate mounting frame 18 can be removably mounted on a pair of vertical posts 26 which extend upwardly from a gauge plate bracket 27. The posts 26 are secured in the bracket 27 by means of pins 28 which pass therethrough.

20 The bracket 27 is in turn mounted on an upturned right edge 29 of the slice-receiving platter 17 by means of bolts 30 which pass through the edge 29 and are threaded into two horizontally extending feet 31 of the bracket 27. The commodity contacting face 14 of the gauge plate 15 is thus located some distance in back of the edge 29 of the slice-receiving platter 17 (as can best be seen in Fig. II). Thus if any small particles of commodity crumble or break away from the main piece of commodity as it is slid along the gauge plate, these small particles will fall not into the interior of the machine but onto the upper surface of the slice-receiving platter 17.

whence they can be easily removed. The slice-receiving platter 17 is mounted by means of four bored ears 32 which are formed on its undersurface and which extend downwardly through elongated apertures 33 in the upper surface of the base 12, into the interior of the base 12. Each one of a pair of substantially parallel shafts 34 extends through two of the ears 32 and is pinned thereto. The shafts 34 are each slidably journaled in a pair of bored tabs 35 which are formed on the undersurface of the base 12. A set of rack teeth 36 is cut in the upper side of each of the shafts 34 near its innermost end and is engaged with one of a pair of pinions 37 cut in longitudinally extending adjusting shaft 38 which is rotatably journaled in a bored ear 39 extending downwardly from the undersurface of the base 12 and in a boss 40 formed on the inner side of the front wall of the base 12. The shaft 38 extends through the boss 40 exteriorly of the base 12 and has an adjusting knob 41 secured on its outermost end by means of a set screw 42. A series of thickness indicia 43 scribed on the conical periphery of the knob 41 cooperates with an index 44 to show the relative thickness of slices of commodity to be severed.

A coiled spring 45, which surrounds the shaft 38, is compressed between a pair of washers 46, one of which lies adjacent the inner face of the boss 40 and the other of which is held in position by a cotter pin 47 passing through the shaft 38. The spring 45 creates a slight amount of friction to prevent the accidental rotation of the shaft 38 due to pressure on the gauge plate 15 resulting from commodities being forced there-against.

The series of indicia 43 is so located on the periphery of the knob 41, and the knob 41 so mounted on the shaft 38, that when a zero indicium 48 of the indicia 43 is in line with the index 44 the forward face 14 of the gauge plate 15 lies substantially in the plane of the cutting edge of the knife 10. Rotation of the knob 41 through the medium of the pinions 37 and rack 36 slides the shafts 34, of the slice-receiving platter 17 and gauge plate 15 to move the face of the gauge plate relative to the plane of the knife 10 and thus to vary the thickness of slices to be severed.

The embodiment of the invention that has been disclosed may be modified to meet various requirements.

Having described my invention, I claim:

1. In a slicing machine having a rotary circular

knife, in combination, a thickness gauge plate having a face substantially parallel to the plane of the cutting edge of said knife, a slice receiver lying behind and below said gauge plate, means for mounting said gauge plate on said slice receiver and mechanism for moving said slice receiver in a direction transverse to the plane of the cutting edge of said knife.

2. In a slicing machine having a rotary circular knife, in combination, a slice receiver, a bracket mounted on said slice receiver, a thickness gauge plate removably mounted on said bracket and above said slice receiver with its face substantially parallel to the plane of the cutting edge of said knife, and mechanism for moving said slice receiver in a direction substantially perpendicular to the plane of the cutting edge of said knife.

3. In a slicing machine having a rotary circular knife, in combination, a thickness gauge plate having a face substantially parallel to the plane of the cutting edge of said knife, a slice receiver, means for mounting said gauge plate on said slice receiver, said slice receiver extending beneath and on both sides of said gauge plate, and mechanism for moving said slice receiver in a direction transverse to the plane of the cutting edge of said knife.

4. In a slicing machine having a rotary circular knife, in combination, a slice receiver, a pair of substantially parallel posts extending vertically upward from said slice receiver, said posts being located near one edge of said slice receiver, a thickness gauge plate removably mounted on said posts with its face substantially parallel to the plane of the cutting edge of said knife and mechanism for moving said slice receiver in a direction substantially perpendicular to the plane of the cutting edge of said knife.

5. In a slicing machine having a base and a rotary circular knife located above said base, in combination, a thickness gauge plate having a face substantially parallel to the plane of the cutting edge of said knife, a slice receiver, means for mounting said gauge plate on said slice receiver, said slice receiver extending beneath and on both sides of said gauge plate, and mechanism mounted in said base and extending beneath said slice receiver for moving said slice receiver in a direction transverse to the plane of the cutting edge of said knife.

GEORGE R. WOOD.
